[57] CLAIM

The ornamental design for a combined pouring spout,
brush wiper and paint can rim protector, as shown.

DESCRIPTION

FIG. 1 is a top, front and right perspective view of a
combined pouring spout, brush wiper and paint can rim
protector showing my new design;

FIG. 2 is a rear elevational view thereof;

FIG. 3 is a side elevational view thereof; and

FIG. 4 is a bottom plan view thereof.

*FIG. 1.**FIG. 2.**FIG. 3.**FIG. 4.*
